REINFORCED CONCRETE FLOOR CONSTRUCTION

Filed Oct. 19, 1925

John Lally
INVENTOR

BY
Robert M. Killgore
ATTORNEY

UNITED STATES PATENT OFFICE.

JOHN LALLY, OF GREAT NECK, NEW YORK.

REINFORCED-CONCRETE-FLOOR CONSTRUCTION.

Application filed October 19, 1925. Serial No. 68,404.

My invention relates to improvements in reenforced concrete floors for buildings and it is my object to construct a floor, partly of pre-cast concrete slabs and partly of poured concrete, which will have cells or air spaces therein to lighten its weight and to reenforce the same with metal bars so that the load carrying capacity will not be lessened, also to have a level, solid ceiling.

10 In the drawing Fig. 1 is a sectional view of the floor construction; Fig. 2 a perspective view of the pre-cast slab; and Fig. 3 a perspective view of the sheet metal dome.

The pre-cast slab *a* which forms the 15 foundation of my present invention, has a solid, flat bottom *1*, outwardly flaring side walls *2*, *3*, *4* and *5*, the top edges of which are provided with a channel or groove *6*.

The thin sheet metal dome *b* has a closed 20 top *7* and sides *8*, *9*, *10* and *11* and is open at the bottom. It is of such size that the lower edges of the sides will nest into the groove *6* of the slab *a*.

The floor is constructed by erecting a form 25 *c*, indicated by dot and dash lines in Fig. 1, and setting thereon the precast slabs *a* at any desired intervals. The reenforcing bars *12* are then laid in place. A sheet metal dome *b* is then set into the groove of each slab *a* 30 and the concrete *d* is poured over the whole embedding the sides of the slabs *a*, the domes *b* and the rods or bars *12* in the concrete. When the form *c* is removed it will be found that the outside of the bottoms of 35 the pre-cast slabs will form portions of the ceiling and that the slabs are solidly locked into the poured concrete matrix by a mortise

and tenon connection due to the fact that the wide portion of the flared sides is above the ceiling level and within the concrete 40 matrix so that they are held in place thereby.

In effect the metal bars and poured concrete form a system of girders and beams which carry and support the pre-cast slabs 45 and their associated domes.

The metal domes are easily set and hold their position during the pouring of the concrete, due to their edges entering the groove in the slab and form a mould for the air 50 cell so that the resultant floor is cellular instead of solid and much lighter than would ordinarily be the case.

The reenforcing rods may be of any desired shape, number and arrangement to obtain the desired strength or to meet peculiar 55 conditions.

I claim:—

1. A cellular member for concrete floors comprising a pre-cast slab consisting of a 60 bottom and outwardly flaring end and side walls the top edges of which are grooved and a sheet metal dome having a top, sides and ends, the edges of the sides and ends engaging the slab grooves. 65

2. A pre-cast slab for reenforced, cellular, concrete floors consisting of a bottom and outwardly flaring side and end walls the top edges of which are grooved and adapted to engage the edges of a sheet metal dome. 70

In testimony whereof I have affixed my signature.

JOHN LALLY.
